Gregory B. Kang; Derek Richmond(57) **CLAIM**

I claim the ornamental design for an aperture for a dispenser cover, as shown and described.

DESCRIPTION

FIG. 1 is a perspective view of my new design for an aperture for a dispenser cover, shown in a first environment with the cover in an open position;

FIG. 2 is a perspective view of the aperture in a second environment with the cover in an open position;

FIG. 3 is a top view of the aperture as seen in FIG. 2, with the cover in an open position;

FIG. 4 is a bottom view of the aperture as seen in FIG. 2, with the cover in a closed position; and,

FIG. 5 is a bottom view of the aperture as seen in FIG. 1, with the cover in a closed position.

The area of stippled shading defines the limit of the claimed design.

The broken line showing of a dispensing cover forms no part of the claimed design.
